METHOD OF SPOTTING CROWN CAPS

Frank J. O'Brien, Pelham, N. Y., assignor to Continental Can Company, Inc., New York, N. Y., a corporation of New York

Application August 2, 1937, Serial No. 157,042

3 Claims. (Cl. 154—40)

The invention relates generally to the art of assembling closure caps of the well known crown type and primarily seeks to provide a novel assembly method embodying the steps of positioning the cap liner pads or disks, affixing center spots to the pads, and stacking the assembled pads and spots for future assembly with crown caps, or assembling the pad and spot units with crown caps directly after the assembling of said units.

In the bottling of beer and similar beverages it is customary to seal the bottles or cans with crown caps equipped with pads of cork or suitable yieldable sealing material faced with an impervious liner disk of aluminum or other foil or treated paper so as to prevent direct contact between the beverage and the pad and also to prevent leakage of gases. Such disks preferably are of the "center spot" type and are smaller in diameter than the pads so as to protect the beverage from pad contact and yet permit sealing contact between the container pouring neck and an annulus of the more effective sealing material of the pad.

Various methods of forming and affixing the "center spots" have been devised, but all such methods of which I am aware applied the "spots" to previously assembled caps and pads, and no one has attempted, heretofore, to first affix the "center spots" to the pads and thereafter insert the pads into the crown caps. The previously known methods of forming spotted caps which seem to have proven most successful are those which employ heat fusible cement in the affixing of the "spots," but in these methods the crown caps or the pads therein had to be heated prior to the assembly of the "spots" in order to fuse the cement on the "spots" and this preheating often proved objectionable. In my improved method this objectionable preheating is avoided by provision of a novel two-stage or temporary, then permanent adhesive union.

According to my improved method, pads of cork or other suitable sealing material are fed along station-to-station. At one station a drop or small dab of a suitable adhesive is applied to the exposed face of the pad, at another station a "spot" coated with heat fusible adhesive is applied to the adhesive bearing surface of the pad to be temporarily united therewith, said "spot" preferably being formed and applied by a cold punch, and at another station a hot plunger is pressed against the temporarily assembled "spot and pad" to fuse the cement carried by the "spot" and apply pressure to permanently unite said

"spot and pad". The "spots" preferably are thus assembled with the pads before the pads are inserted into crown caps, and after the "pad and spot" units are thus assembled they are stacked for insertion into crown caps at a future time, or they may be directly inserted into the crown caps by use of either hot or cold plungers.

With the above and other objects in view which will more fully appear, the nature of the invention will be more clearly understood by following the description, the appended claims, and the several views illustrated in the accompanying drawing.

In the drawing:

Figure 1 is a diagrammatic longitudinal section showing the various steps of my improved method.

Figure 1A is a diagrammatic longitudinal section illustrating a modified step of the invention in which the assembled "pads and spots" are directly inserted into crown caps instead of being stacked.

Figure 2 is a vertical cross section taken at the "spot" punching station.

In the drawing 5 designates a table, or other suitable support, and 6 a conveyor for the sealing pads 7 of cork or other suitable material. The conveyor 6 may take the form of a rotary disk or plate, a finger bar or even an endless belt having suitably spaced apertures or seats 8 therefor for accommodating the pads or disks 7. Movement is imparted to the conveyor by any approved means for advancing the pads 7 step-by-step or from station-to-station.

Five such stations are diagrammatically indicated in the drawing and designated #1, #2, #3, #4 and #5. At station #1 the pads 7 are fed one-by-one into the conveyor seats 8 from a supply magazine 9. As each pad reaches station #2 a drop or dab 10 of adhesive is applied centrally of the exposed surface thereof by a dropper, squirt pump, fountain or any other suitable form of applicator designated 11. Positioned at station #3 is a die 12 and a reciprocable cold punch 13, and as each pad is brought beneath this equipment a "center spot" is cold-punched from a strip 15 of fusible-adhesive-coated material, preferably aluminum foil, and applied in centered relation to the underlying pad 7 and on the adhesive dabbed surface of said pad. The "center spot" is thus temporarily united with the pad and held against movement relative thereto during travel of said pad away from station #3.

The foil strip 15 may be supplied from a roll 55

16 and drawn, step-by-step, over the die 12 by suitably driven feed rolls 17.

Upon reaching station #4, the temporarily assembled pad and "center spot" unit is pressed 5 by a hot plunger 18, the heat and pressure serving to fuse the adhesive borne by the pad engaging face of the "center spot" 14 and permanently unite said pad and spot. The duration of the heat and pressure application may be varied as 10 may be found desirable in order to obtain the most perfect union obtainable.

The pad and "center spot" units are next successively fed to a stacking station #5 where they are stacked, preferably under pressure, by any 15 suitable mechanism. In this diagrammatic illustration I have shown an upright stack or magazine 19 into which the pad and "center spot" units are forced, one-by-one by the plunger 20 reciprocable through the support aperture 21. 20 A weight 22 will suffice to hold the units under pressure. The assembled units may thus cool and permanently set, under pressure, in the stack.

In Figure 1A of the drawing I have illustrated 25 a modified step of my improved method in which the assembled pad and "center spot" units are directly inserted into crown caps, instead of being stacked. A hot or cold plunger 23 may be mounted at station #5A to reciprocate through 30 the support aperture 21, and a suitable carrier 24 may be movably mounted beneath said aperture and equipped with seating means 25 for crown caps 26. Each time the pad and "center spot" unit conveyor 6 brings a unit over the aperture 21 at station 5A the plunger 23 will be reciprocated to strip the unit from the conveyor and insert it into the crown cap 26 supported therebeneath.

As has been previously stated, any suitable 40 mechanism may be employed in practicing the

method herein disclosed without departing from the scope of the invention as defined in the appended claims.

What I claim is:

1. The method of assembling cap pads and 5 "center spots" which comprises positioning individual sealing pads, applying a dab of adhesive to each pad, cold-punching and applying a "center spot" of fusible adhesive coated material to the adhesive dabbed face of each pad to 10 temporarily unite said pads and "center spots", and pressing each "center spot" with a hot plunger to fuse the fusible adhesive coating of the "center spots" and permanently unite said 15 pads and "center spots".

2. The method of assembling cap pads and heat fusible adhesive coated "center spots" which 20 comprises positioning a pad, affixing a "center spot" to the pad by application of heat and pressure, promptly stacking the assembled pads and "center spot" units, and applying pressure to the stacked pad and spot assemblies to maintain the intimate adhesion of the pads and spots as they cool.

3. The method of assembling cap pads and 25 "center spots" which comprises moving successive sealing pads station-to-station, applying a dab of adhesive to each pad at one station, cold-punching and applying a "center spot" of fusible adhesive coated material to the adhesive 30 dabbed face of each pad at another station to temporarily unite said pads and "center spots", applying a hot plunger to the temporarily united pads and spots at another station in order to more permanently unite them, promptly stacking the successively united pad and "center spot" units, and applying pressure to the stacked pad and spot assemblies to maintain the intimate adhesion of the pads and spots as they cool.
